The ornamental design for a metallic core of rubber crawler, as shown and described.

DESCRIPTION

FIG. 1 is a perspective view of a metallic core of rubber crawler according to the present invention;

FIG. 2 is a front view thereof;

FIG. 3 is a top view thereof; and,

FIG. 4 is a right side view thereof.

The long dash short dash broken line shown in FIGS. 1, 2, and 4 represents the bounds of the claimed design and the short dash broken lines are included for the purpose of illustrating environmental structure only and form no part of the claimed design.
